OVERHEAD GARAGE DOOR

John H. Burr, Denver, Colo.

Application January 8, 1951, Serial No. 204,925

4 Claims. (Cl. 160—191)

1

This invention relates to an overhead garage door of the type divided into upper and lower portions hinged together horizontally across the center of the door opening. Doors of this type have been objectionable due to the fact that the lower portion of the door required such a space to swing inwardly as to make their use impractical on small garages due to the limited distance between the garage door and car therein.

The principal object of this invention is to provide a door construction of the above-described type in which the lower portion of the door will move substantially vertical as it moves to or away from the closed position so that it will clear the bumper of a closely positioned car without car interference.

The invention is designed more particularly as an improvement over the overhead garage door shown in applicant's prior Patent No. 2,334,749.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a vertical section through the improved door, taken on the line 1—1, Fig. 6, illustrating it in the completely closed position;

Fig. 2 is a similar sectional view, illustrating the initial opening or final closing position of the improved door;

Fig. 3 is a similar sectional view, illustrating an intermediate position of the door;

Fig. 4 is a similar sectional view, illustrating the door in the completely open position;

Fig. 5 is an enlarged, fragmentary, detail, perspective view, illustrating a hinged angle bracket employed with the improved door;

Fig. 6 is an inside face view of the door in place in a wall;

Fig. 7 is an enlarged, fragmentary, detail, perspective view, illustrating a hinge and latch fixture employed with the improved door; and

Fig. 8 is a similar perspective view, illustrating a latch lever construction employed on the improved door.

In the drawings a garage wall is indicated at 10, with side door casings 11 and a head door casing 12 incorporated therein. The floor line of the

2

garage in which the door is installed is indicated at 13.

The improved door comprises an upper door portion suspended by means of inside suspension hinges 15 from the head casing 12. The upper portion 14 occupies substantially the entire upper half of the door opening. A lower door portion 16 closes the lower half of the door opening and is suspended from the upper portion 14 by means of suitable outside hinges 17. The door is stopped in the closed position by means of a suitable door stop strip 18 nailed or otherwise secured to the side casings 11 and the head casing 12. The lower portion of the door is prevented from swinging inwardly by means of curved stop straps 19 secured to the side casings 11 at the bottom thereof.

A channel-shaped hinge fixture 20 is secured to each side casing 11 above the middle of the latter by means of suitable bolts 21. A swinging link member 22 is suspended from a hinge pin 23 in the lower portion of each fixture 20. The lower extremity of each link member 22 is hingedly connected at 24 to the rear extremity of the long leg of an L-shaped, hinged angle bracket 25. The forward extremity of the short leg of each angle bracket 25 is turned downward and mounted on a second hinge pin 26 extending through a projecting flange on an angle attachment member 27. The attachment members 27 are secured at opposite sides of the inside face of the lower door section 16 by means of suitable attachment bolts 28. A tension spring 31 extends from an ear 29 formed on the lower extremity of each link member 22 upwardly to an attachment loop 30 attached in one of the hinge fixtures 20 above the hinge pin 23 therein.

It will be noted that each L-shaped angle bracket is so mounted that when the door is in the closed position, the shorter leg will extend downwardly to its hinge pin 26 at an acute angle to the plane of, and out of contact with, the attachment member 27, as shown in Figs. 1 and 5.

Let us assume that the door is in the closed position of Fig. 1. To open the door, the center portion thereof is forced or pulled inwardly to the position of Fig. 2. In moving to this position, the lower part of the lower portion 16 of the door rotates about the axes of the hinge pins 26 with little or no inward movement, and the upper part of the lower portion of the door swings inwardly until it rests against the shorter legs of the L-shaped angle bracket members 25, as shown in Fig. 2.

It will be noted that, in moving to the partially

opened position of Fig. 2, there has been no inward movement of the lower portion of the door, so that it will not swing against the bumper of an adjacent car, and that in moving to the position of Fig. 3, the lower portion of the door has moved inwardly but slightly, so that very little car interference is encountered.

The springs 31 in Fig. 1 are exerting no lifting action of any kind upon the door. When the door reaches the position of Fig. 2, however, with the 10 lower door section against the angle brackets 25, the springs 31 exert a lifting action on the lower door portion to elevate it to the position of Fig. 3, thence to the position of Fig. 4.

From the position of Fig. 3 the lower portion 15 of the door moves upwardly and outwardly to the position of Fig. 4, where the entire weight is supported by the springs 31. The tension in the springs is pre-set so that when the resisting toggle action of the two door sections is broken, as in Fig. 2, the springs will automatically elevate the door to the open position.

The door is locked in the closed position by means of two elongated latch bars 32 extending through latch guides 33 at the sides of the upper door section 14. The extremities of the latch bars 32 ride over a latch hook 34 formed on each hinge fixture 20, as shown in Fig. 7, to automatically latch the door closed.

The bars 32 extend from hinge pins 35 in a latch lever 36. The latch lever is pivoted on a pivot bolt 37 mounted in a latch frame 38 at the middle of the door. The latch lever 36 is provided with a projecting handle 39 by means of which the lever may be swung to withdraw the extremities of the bars 32 horizontally from engagement with the hooks 34 to release the door. The bars 32 are constantly urged to the engaging position by means of a tension spring 40.

The lever 36 may be locked against movement by means of a swinging lock member 41 pivoted on the frame 38 so that it may swing downwardly behind the lever 36 to prevent unlocking movement thereof. The lock member 41 rests on a key-actuated support 42 mounted on a lock tumbler 43. To lock the door it is only necessary to drop the locking member 41 onto the support 42. To 45 unlock the door, it is necessary to rotate the key tumbler barrel 43 to cause the support 42 to swing to the left in Fig. 8 to raise the locking member 41 out of the path of the lever 36.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. An overhead garage door construction comprising: side door casings; a horizontal head casing supported by said side door casings; an upper door portion; inside hinges suspending said upper door portion from said head casing; a lower door portion; outside hinges suspending said lower door section from said upper door portion; a hinge fixture secured to the inside of each side door casing; a swinging link suspended from each fixture; a tension spring attached at its one extremity to each fixture above the link thereon and secured at its other extremity to the swinging extremity of the adjacent link; an L-shaped bracket member hinged at one extremity to the swinging extremity of each of said links and extending toward said lower door portion, thence downwardly therealong; and pivot means securing the lower extremity of each L-shaped bracket member to said lower door portion.

2. An overhead garage door construction as recited in claim 1 in which the downwardly extending portion of each L-shaped bracket member forms an acute angle with said lower door portion when in the closed position to allow said latter portion to initially swing inwardly against said bracket members.

3. An overhead garage door construction as recited in claim 2 having a stop plate secured to each side frame member adjacent the bottom of the latter to prevent the lower edge of said lower door portion from swinging inwardly until it has raised a predetermined distance.

4. An overhead garage door construction as recited in claim 2 in which the pivot means comprises an angle member secured vertically at each side of said lower door portion; and a pivot member securing the lower extremity of each link adjacent the lower extremity of one of said angle members so that the upper portion of each angle member may swing inwardly into contact with the adjacent bracket member.
